UNITED STATES PATENT OFFICE.

ELI J. GILPIN AND OLIVER HELMICK, OF FOWLER, INDIANA.

SAFETY-CUSHION FOR ELEVATORS.

SPECIFICATION forming part of Letters Patent No. 568,345, dated September 29, 1896.

Application filed February 12, 1896. Serial No. 579,029. (No model.)

To all whom it may concern:

Be it known that we, ELI J. GILPIN and OLIVER HELMICK, citizens of the United States, and residents of Fowler, county of 5 Benton, and State of Indiana, have invented certain new and useful Improvements in Safety-Cushions for Elevators, of which the following is a specification, reference being had to the accompanying drawing, forming a 10 part thereof, in which similar letters of reference indicate corresponding parts.

This invention relates to an improved safety-cushion for elevators, and has for its object to so construct a cushion as to render 15 it adaptable for taking the impact of an elevator-car in case of its accidentally dropping. The device will be of such a flexible character as to prevent a sudden stopping of an elevator-car, whereby passengers therein will 20 not receive any injurious results.

The invention will be hereinafter fully described, and specifically set forth in the annexed claims; and the accompanying drawing, showing a vertical elevation of the lower 25 portion of an elevator-shaft having our improvement contained therein, will illustrate the invention, in which we primarily provide a supplemental well A, which will be located upon a vertical line with the shaft of the elevator and immediately below the lower floor 30 at which the elevator-car is adapted to land. The said well A will comprise four solid walls a, and it must be strong enough in construction to bear a considerable pressure of compressed air in the event of the elevator accidentally falling.

In the lower portion of the well A and resting upon the bottom thereof is a flexible inflatable bag B, which is provided with a valve 40 b, adapted to feed air thereto. This said bag may be inflated under pressure by means of any suitable pump and it will be constantly maintained in an inflated condition.

Resting upon the upper surface of the bag 45 B is a platform C, which is preferably bound around its four edges by a rubber binding c, which will maintain it in air-tight engagement with the walls of the well A, which said walls must be perfectly smooth, and they are preferably supplied with a metallic lining a'. Resting upon the platform C is a series of

springs D, which springs are preferably coiled springs of a conical contour, but any other suitable form of spring may be employed. Other coiled springs D' are then built up in 55 a vertical series to a height equaling the depth of the pit between the platform C and the upper edge of said pit.

To hold the springs together, we provide between each set thereof auxiliary platforms C', and a similar platform C² rests upon and is secured to the upper set of springs, whereby 60 a spring-cushion is formed, which, in combination with the air tank or bag B, will form a very flexible base for the elevator-car to 65 strike in the event of its accidentally dropping.

The ordinary vertical guides for the elevator-car E should extend to the bottom of the pit, and its floor e should be provided with 70 a projecting flange e' in order to supply a large area, which will tend to compress air within the well A while the elevator-car is in the act of falling.

To prevent rebounding of the elevator-car 75 to any great height, we provide upon the inner walls of the well A spring-catches a², which are maintained in a normally-extended position by springs a³. The flange e' of the floor e of the elevator-car depresses the said 80 catches upon the downward movement of the elevator-car, but upon the rebound the catches will engage with the flanges e' and prevent further upward movement of the elevator-car.

Having thus described our invention, what 85 we claim as new, and desire to secure by Letters Patent, is--

1. The combination with an elevator-shaft of a supplemental well, an inflated bag in said well, and a platform and a series of springs 90 resting on said bag, said platform being fitted by air-tight joints to the inner wall of the well, substantially as shown and described.

2. A safety attachment for elevator-shafts comprising a solidly-built supplemental well 95 located beneath the lower landing of said shaft and an inflatable bag and an air-tight platform and a series of springs and auxiliary platforms, substantially as shown and described.

3. The combination of a solidly-built supplemental well located beneath the elevator-

shaft and having an inflatable bag and air-tight platform and a series of springs and platforms therein, and spring-pressed catches projected inwardly from its walls; with an elevator-car having projecting flanges upon its floor, substantially as shown and described.

5 In testimony that we claim the foregoing as our invention we have signed our names,

in presence of two witnesses, this 7th day of February, 1896.

ELI J. GILPIN.
OLIVER HELMICK.
